5 Claims. (Cl. 202—185)

Apparatus of a compact and simple character for enabling small supplies of fresh water to be distilled is required for many purposes, and is particularly desirable to form part of the equipment of a ship's lifeboat for obtaining fresh water from seawater should the quantity of fresh water normally carried by such boats become exhausted owing to the length of time during which the lifeboat may be afloat before the occupants reach shore, or are picked up.

According to this invention the distilling apparatus of comparatively small dimensions so as to be readily portable comprises as a unitary structure a cylindrical vertical boiler or evaporator having an interior firebox and combustion chamber surrounded by an annular water space, a condenser and means for enabling cooling water to be circulated therethrough. An anti-priming baffle plate is fitted in the boiler shrouding the vapour outlet to the condenser, and at the base of the latter a small filter may be provided having an outlet bend forming a water seal. The firebox and combustion chamber may be corrugated to increase heating surface, and means such as a gauge glass provided for indicating the water level in the boiler and the boiler may be lagged. The condenser is preferably of tubular type having an annulus surrounding the vapour pipe through which cooling water is adapted to be circulated, which, in the case of a ship's boat, would be seawater circulated by the hand pump forming part of the usual equipment of a ship's lifeboat.

One embodiment of the invention is illustrated in the accompanying drawings in which:

Fig. 1 is an elevation and

Fig. 2 is a plan of a distilling apparatus.

Fig. 3 is a vertical section of Fig. 1.

Fig. 4 is a vertical section of a three-way cock for controlling the water supply to the condenser or the boiler feed, and

Fig. 5 is a section of the boiler feed connection.

Fig. 6 is a plan view of the baffle plate in the boiler, and

Fig. 7 is an oil burner fitting for use with the boiler.

In the construction illustrated, the cylindrical boiler shell 1 is detachably secured by its flange 2 to a lower plate 3 perforated with a series of air holes 3a the plate being spaced by distance pieces 4 from a base plate 5. Within the boiler shell is a conical firebox and combustion chamber 6 tapering towards the boiler shell cover 7 which takes the form of a domed cap, the flange 8 on which is detachably secured to the top

flange 9 of the boiler shell by bolts and wing nuts 10. A suitable packing is preferably compressed between the flanges. The upper narrower end of the combustion chamber is secured to a sleeve 11 externally threaded at its upper end and having a flange 12 between which and a ring nut 13 carrying the funnel 14a is secured the inner end of a conical baffle plate 14 which extends from the inner part of the cover 7 downwardly nearly to the tubular wall of the boiler shell 1 leaving only a restricted annular outlet for the vapour generated in the boiler. The baffle plate has a series of perforations 15 and the plate is recessed at 16, the recess being disposed opposite the vapour outlet 17, preventing any tendency to priming and minimizing the effect of turbulence while allowing for an easy exit of the generated vapour. Near the base of the boiler shell is a series of holes 39 and these together with the air space between the foot plate 5 and base plate 3 and the air holes 3a in the latter, permit inlet of the necessary air for effective combustion. The vapour passes by way of the branch 17 and pipe 18 to the condenser. This consists of a tubular outer casing 19 held between end caps 20 through which passes the inner vapour tube 21 forming a continuation of the pipe 18 and branch 17 connected up by couplings 22. In the arrangement shown the condensed vapour passes into a filter 23, carried from the base of the tube 21, containing granulated charcoal or other filtering medium, and at the base of the filter is an outlet pipe 24 forming a siphon bend and water seal. The condenser 19 has a lower water inlet 25 and an upper discharge 26, the circulating water passing from the inlet to the discharge by way of the annulus between the inner vapour tube 21 and the outer casing 19. A three-way cock 27 is connected by its branch 28 to a cold water supply, which in the case of a ship's lifeboat would be circulated through the condenser by the manually operated pump of the usual lifeboat equipment, the cock having branches 25a, 29 to which are led pipe connections to the condenser circulating water inlet and to the boiler feed connection 30. The boiler is fitted with a gauge glass 31 to indicate the water level in the boiler, the gauge being protected by a guard 32. The boiler shell is lagged at 33. The connection 30 may have a tap branch 40 for use only when heating fresh water in the apparatus.

In operation, the boiler is filled with water to the desired level determined by the gauge glass by

turning the plug of the cock 27 to put the supply branch 28 in communication with the boiler feed connection 30. The fire is then lighted in the firebox 6 by dropping burning paper or lighted oily waste down through the top of the conical firebox, the funnel 14a being, if necessary, removed for this purpose. Wood may then be fed into the firebox. The suction pipe of the pump, where a circulating pump is being used, is then coupled up to a suitable water supply, or put overboard from the ship's boat as the case may be, and the plug of the cock 27 is turned to put the inlet branch 28 in communication with the circulating water inlet 25, the boiler feed 30 being shut off. When vapour is generated and passes by way of the outlet 17 and pipe 18 into the condenser tube 21, cooling water is circulated through the condenser annulus by working the pump. The water of condensation passes into the filter 23 and through the siphon bend 24 and may be collected in any suitable vessel. The filter 23 and siphon outlet 24 may if desired be dispensed with. As evaporation proceeds and the water level in the boiler falls, the plug of the cock 27 is turned to shut off the condenser and put the water supply in communication with the feed branch 30 by way of the pipe 27a, the boiler being again filled up. After being in use some time the boiler and furnace need to be cleaned, and to effect this the ash may be removed from the firebox 6 by disconnecting the boiler shell from the lower plate 3 completely opening the bottom of the firebox, and similarly by loosening the nuts 10 and removing the boiler cover 7 and inverting the boiler, the residual heavy brine may be emptied from the water space. It has been found in practice that the boiler may be refilled with seawater and evaporated about four times before it and the furnace need to be cleaned.

Alternatively the branch 26 on the condenser may be used as the cooling water inlet and the branch 25 as the outlet by way of the cock 27, the cock having a third or delivery branch on the side instead of the open bottom branch 28. The condenser annulus may be provided with a spiral baffle to increase the effective path of the cooling water.

With such an apparatus when used in connection with a ship's lifeboat, in order to provide emergency fuel a few of the usual air cases of the lifeboat may be replaced by wood bundles, or parts of the wooden structure of the lifeboat itself might be used as fuel, or the oars, bottom boards or mast could be so used, while a further source of fuel would be driftwood obtained when afloat.

Alternatively to the burning of wood or similar combustible matter, the distilling apparatus may be fitted with an oil burner. With this object the arrangement shown in Fig. 7 is utilized, the ring casing 34 of the burner having upper and lower flanges 35, 36 and an access door 37. This is fitted by disconnecting the perforated lower plate 3 and bolting the upper flange 35 of the burner casing to the lower flange 2 of the boiler, the disconnected base plate 5 and its distance pieces 4 being connected to the lower flange 36 of the oil burner casing. Air apertures 38 are formed in the lower wall of this oil burner casing, an air supply being afforded through these

and through the air space between the base plate 5 and perforated plate 3.

The whole apparatus could be made very compact, a suitable size for the boiler being about 9 inches diameter by 18 inches high, so that it may be readily stored in the restricted space available on a ship's lifeboat, the apparatus, though not necessarily restricted to marine use, offering a simple and valuable means of saving life at sea in case of marine disasters and particularly those due to enemy action, where the ship's lifeboats are frequently at sea for long periods before the survivors are rescued.

We claim:

1. A unitary structure portable distilling apparatus, comprising a cylindrical vertical boiler, an interior conical firebox and combustion chamber in the boiler forming therewith an annular water space, a detachable cover for the boiler carrying a vapour outlet pipe to a condenser, a baffle plate carried from the cover and shrouding the vapour outlet, said condenser, and means for controlling the circulation of cooling water through the condenser.

2. A unitary structure portable distilling apparatus, comprising a cylindrical vertical boiler, an interior firebox and combustion chamber in the boiler forming with the boiler shell an annular water space, a condenser separate from the boiler but carried therefrom, a filter fitted at the base of the condenser, a water seal at the base of the filter, and means for controlling the circulation of cooling water through the condenser.

3. A unitary structure portable distilling apparatus, comprising, a cylindrical vertical boiler, an interior conical firebox and combustion chamber in the boiler forming therewith an annular water space, a detachable cover for the boiler carrying a vapour outlet pipe, a perforated baffle plate carried from the cover and shrouding the vapour outlet, a water cooled condenser separate and exterior of the boiler, and means for controlling the circulation of cooling water through the condenser.

4. A unitary structure portable distilling apparatus, comprising, a cylindrical vertical boiler, an interior conical firebox and combustion chamber in the boiler forming therewith an annular water space, a detachable cover for the boiler carrying a vapour outlet pipe, a baffle plate carried from the cover and shrouding the vapour outlet, a recess in the baffle plate remote from the vapour outlet, a water cooled condenser separate and exterior of the boiler, and means for controlling the circulation of cooling water through the condenser.

5. A unitary structure portable distilling apparatus, comprising, a cylindrical vertical boiler, an interior conical firebox and combustion chamber in the boiler forming therewith an annular water space, a detachable cover for the boiler carrying a vapour outlet pipe, a baffle plate carried from the cover and shrouding the vapour outlet, a water cooled condenser separate and exterior of the boiler, and a three-way cock connected to the condenser to the boiler and a cooling water supply.
